ELECTRIC SWITCH

Robert F. Sambleson, Bridgeport, Conn., assignor
to General Electric Company, a corporation of
New York

Application November 15, 1935, Serial No. 49,930

18 Claims. (Cl. 200—153)

The present invention relates to electric switches of the type having liquid contact circuit closers for controlling the flow of current.

The object of my invention is to provide an improved construction and arrangement in switches of this type, and for a consideration of what I believe to be novel and my invention attention is directed to the accompanying description and the claims appended thereto.

10 In the accompanying drawings, Fig. 1 is a sectional elevation of a switch embodying my invention taken on line 1—1 of Fig. 2; Fig. 2 is a top plan view of the switch shown in Fig. 1, parts of the switch being broken away; Fig. 3 is a sectional view taken on line 3—3 of Fig. 1; Fig. 4 is a diagrammatic view showing the construction and operation of the liquid contact circuit closer; Fig. 5 is a side elevation showing the manner of mounting the switches crosswise in an outlet box; Fig. 6 is a sectional side elevation taken on line 6—6 of Fig. 7 of a double pole switch embodying my invention; Fig. 7 is a top plan view of the switch shown in Fig. 6, parts of the switch being broken away; Fig. 8 is a sectional elevation taken on line 8—8 of Fig. 6; Fig. 9 is a diagrammatic view showing the operation of the switch; Fig. 10 is a diagrammatic view showing the operation of the switch as a three-way switch; Fig. 11 is a side elevation showing another arrangement of the switches mounted crosswise in an outlet box; Fig. 12 is a sectional side elevation taken on line 12—12 of Fig. 13 of a four-way switch embodying my invention; Fig. 13 is a top plan view of the switch shown in Fig. 12, parts of the switch being broken away; Fig. 14 is a sectional elevation taken on line 14—14 of Fig. 12; and Fig. 15 is a diagrammatic view showing the operation of the four-way switch.

Referring to Fig. 4, I have illustrated my invention using a liquid contact circuit closer having a pair of cup-shaped metal terminals 1 which are separated by an insulating diaphragm 2 of a refractory material, such as a ceramic material. The edges of the terminals are sealed by a bead 3 of glass which also seals the junctions between the diaphragm and the terminals. Within the space enclosed by the terminals is a suitable quantity of mercury 4 which forms the conducting medium between the terminals. In the manufacture of the circuit closer, the space between the terminals is evacuated and filled with hydrogen at a pressure of one or more atmospheres which increases the current interrupting capacity of the circuit closer. As shown by the full lines in Fig. 4, the diaphragm 2 is provided with

an opening 5 which is submerged in the mercury when the circuit closer is in the current-conducting position. When the circuit closer is in the current-interrupting position shown in dotted lines in Fig. 4, the opening 5 is above the mercury, and the circuit between the terminals is therefore broken by the insulating diaphragm 2. Due to the construction of the circuit closer, the interruption of the circuit between the terminals takes place in the mercury as the circuit closer 5 is turned so that the opening 5 in the diaphragm approaches the dotted line position. The above described construction is illustrative of liquid contact circuit closers which are suitable for use in switches embodying my invention. 10

The switch shown in Figs. 1 to 3 inclusive is supported in a housing 6 of molded insulating material. Between the terminals 1 of the liquid contact circuit closer and the side walls of the housing are contact strips 7, each of which is 20 provided with a projection 8 which fits into a complementary depression 9 in the adjacent terminals. The projections 8 and the depressions 9 provide ball and socket connections between the terminals and the contacts 7 thereby supporting 25 the circuit closer for rotation about its axis. The wiping action between the contacts and the terminals tends to prevent increased contact resistance. Prior to the assembly of the contacts 7, the ends of the contacts are bent inwardly 30 and given an initial set so that they exert an inward pressure on the terminals thereby increasing the contact pressure. The side walls of the housing prevent spreading of the contacts so that the circuit closer is securely held between 35 the contacts. On the upper side of the circuit closer is a handle 10 on the under side of which is a groove 10a which fits over the bead 3. The handle 10 is provided with projecting flanges 11 on each side which rest on the upper surface of 40 the terminals 1. On the under side of the flanges 11 are projections 12 which fit into depressions 13 in the terminals and prevent relative rotation between the handle and the terminals. Sidewise displacement of the handle relative to the circuit 45 closer is prevented by the groove 10a which fits over the bead 3. The handle is held in place on the circuit closer by four spring strips 14 which bear on the upper surface of flanges 11. The spring strips 14 are secured to a supporting strip 50 15 of insulating material by means of hollow rivets or eyelets 16. Two of the rivets 16 are also used to secure the contacts 7 to the supporting strip 15. The upper surfaces of the flanges 11 on the handle are provided with depressions 17 into 55

which the curved ends 18 of the spring strips 14 are adapted to fit. When the ends 18 rest in the depressions 17, the handle is resiliently held in this position. The spring strips also tend to force the circuit closer between the contacts 7 and thereby increase the contact pressure between the terminals and the contacts.

In the assembly of the switch, the contacts 7 are arranged on each side of the liquid contact 10 circuit closer with the projections 8 resting in the depressions 9 in the terminals 1. The handle 10 is then placed on the circuit closer so that the projections 12 fit in the depressions 13 in the terminals. The spring strips 14 are then 15 assembled on the supporting strip 15, and the spring strips are riveted to the supporting strip by means of the hollow rivets 16. Two of the rivets 16 have the additional function of securing the contacts 7 to the supporting strip 15. 20 When the riveting operation is completed, the circuit closer, the handle 10, the contacts 7, and the spring strips 18 are all held in assembled relation on the supporting strip 15 and the circuit closer is supported between the contacts 25 for rotation about its axis. The assembly is then inserted within the housing so that the ends of inserts 19 molded in the housing project through the hollow rivets 16. The upper ends of the inserts 19 are then spun over, holding 30 the assembly in the housing. The housing is provided with slots 20 adjacent the side walls in which the contacts 7 fit. These slots hold the contacts 7 vertical, and the bottom of the slots provides supports for the lower edges of the contacts. 35 The electrical connection to the contact strips 7 is made by means of terminal screws 21a threaded into the inserts 19. The upper end of the housing 6 is closed by a cover 21.

The switch described above is adapted for 40 group mounting crosswise in a conventional outlet box 22, as shown in Fig. 5. The bottom of the housing 6 is provided with two projecting bosses 23 which project through openings in a mounting strap 24 secured in the top wall of the box. The projections 23 are provided with slots 45 25 which extend below the lower surface of the strap and which are adapted to receive pins for holding the switch to the strap. By having the mounting strap 24 support the switches from a point below the top of the switch, it is possible 50 to mount the switches in the outlet box and subsequently to pull the wires up the sides of the box and attach them to terminal screws 21a which are located on the top of the switch housing. After the switches are mounted in the outlet box, a cover plate 26 is secured across the top of the box. This cover plate is provided with openings 27 which fit over the projecting portion 28 on the switch cover 21, and the cover plate therefore assists in holding the switches in the outlet box.

When the switches are mounted in the outlet box, the right-hand end of the switch, as shown in Fig. 1; is mounted at the top of the 65 outlet box. When the switch is mounted in this position, the movement of the handle 10 to the upper position, shown in full lines in Fig. 4, causes the circuit to be closed between the terminals 1 of the circuit closer. The movement of the handle to the lower position shown in dotted lines in Fig. 4, causes the circuit between the terminals of the circuit closer to be opened.

The switch shown in Figs. 6 to 10 inclusive is a double-pole or a 3-way switch which is adapted 75 for mounting crosswise in an outlet box. This

switch uses two liquid contact circuit closers of the construction shown in Fig. 4, which are arranged one above the other in a housing 30 of molded insulating material. The lower circuit closer is supported by contact strips 31 which are provided with projections 32 which fit into depressions 33 in each of the terminals and support the circuit closer for rotation about its axis in the same manner as the contact strips 7 shown in Fig. 1. The upper liquid contact 10 circuit closer is similarly supported between two contact strips 35. Over each of the terminals 1 are rings 36 of insulating material which are provided with intermeshing teeth 37. The rings 36 are located on the terminals by projections 38 which fit into depressions 39 in the terminals. The rings 36 are held in place on the terminals by contact strips 31 and 35, and it is apparent that with this construction the liquid contact 15 circuit closers turn in unison and in opposite 20 directions. On the upper circuit closer is a handle 40 which is provided with a groove 41 on the under side which fits over the bead 3. Molded into the handle are metal inserts 42 the forked ends 43 of which project from opposite sides 25 of the handle. The ends 43 of the metal inserts 42 extend between the terminals of the upper liquid contact circuit closer and the rings 36, and the ends are bent up into depressions 44 in the rings to hold the handle on the circuit 30 closer. At the four corners of the upper liquid contact circuit closer are spring strips 45 which bear on the rings 36. The spring strips 45 exert a downward pressure on the circuit closer which increases the contact pressure between the terminals of the circuit closers and the contacts 31 and 35. The spring strips are provided with curved ends 46 which fit into depressions 47 in the rings 36 and resiliently hold the circuit closers in either extreme position. The spring 40 strips 45 and the contacts 31 and 35 are secured to a supporting strip 48 by means of hollow rivets 49.

In the assembly of the switch the handle 40 is placed on the upper liquid contact circuit closer, 45 and the rings 36 are placed on the terminals over the ends 43 of the inserts 42 molded in the handle. The rings 36 are then turned so that the projections 38 fit in the depressions 39 in the terminals, and the ends 43 of the inserts 42 are bent up into recesses 44 in the rings. This 50 locates the handle 40 with respect to the upper liquid contact circuit closer and secures the handle thereto. The rings 36 are then assembled on the terminals of the lower liquid contact circuit closer and the lower circuit closer is arranged so that the teeth 37 of the rings 36 mesh. The contact strips 31 and 35 are then placed against the terminals so that the projections on the contact strips fit within the depressions in 60 the terminals. The spring strips 45 are then placed on the contact strips and the spring strips and the contacts 31 and 35 are riveted to the supporting strip 48 by means of the hollow rivets 49. The liquid contact circuit closers, the 65 handle, and the contact strips are now assembled as a unit. This assembly is then inserted into the housing 30 so that the ends of inserts 50 which are molded into the housing project through the hollow rivets 49 and the projecting 70 ends of the inserts 50 are spun over the rivets thereby holding the switch within the housing. The line conductors are connected to the switch by means of terminal screws 51 which are threaded into the inserts. As shown in Fig. 7, the con- 75

tact strips 31 which engage the lower circuit closer are connected respectively to the terminals marked A and B, and the contact strips 35 which bear against the terminals of the upper circuit closer are connected respectively to the terminals marked C and D.

Figs. 5 and 11 show the double-pole switch mounted in the outlet box 22. When so mounted, the lower end of the housing 30 projects through an opening in the strap 24, and the openings 52 in bosses 53 extend below the mounting strap. The switch is held in place by pins passing through these openings. The upper side of the switch is enclosed by a cover 54 having a boss 55 which projects through one of the openings 27 in the cover plate 26.

The operation of the double-pole switch is shown in Fig. 9. When the handle 40 is in the upper position, circuits are completed from terminal A to terminal B and from terminal C to terminal D. When the handle is in the lower position shown in dotted lines in Fig. 9, these circuits are broken.

By changing the location of the opening 5 in the diaphragm of the lower liquid contact circuit closer and by connecting the terminals A and C, this switch may be used as a three-way switch. When these changes are made, the operation of the switch is shown in Fig. 10. When the handle 30 is in the upper position shown in full lines, a circuit is completed from the terminal D to the terminals A and C, and when the handle is in the lower position shown in dotted lines, a circuit is completed from the terminal B to the terminals A and C.

The switch shown in Figs. 12 to 15 inclusive is a double-pole reversing switch or a four-way switch which is adapted for mounting crosswise in an outlet box. This switch uses four liquid contact circuit closers of the construction shown in Fig. 4, which are arranged in two pairs, one pair being above the other in a housing 56 of molded insulating material. The inner terminals of each pair of circuit closers are adjacent each other, and the outer terminals are adjacent the side walls of the housing 56. Between the outer terminals of the circuit closer and each side wall of the housing is a contact strip 57 having two projections 58 and 59 which fit respectively into depressions 60 and 61 in the terminals. Between the adjacent terminals of each pair of circuit closers in a contact strip 62 having a U-shaped portion which is provided with oppositely facing projections which fit into depressions 63 in the terminals. The projections on the contact strips and the depressions in the terminals provide ball and socket connections which support the circuit closers for rotation about their axes. Over each of the terminals of the circuit closers are rings 64 of insulating material which are provided with intermeshing teeth 65. The rings 64 are located on the terminals by projections 66 which fit into depressions 67 in the terminals. The rings 64 are held in place on the terminals by the contacts 57 and 62, and it is apparent that with this construction the upper and lower liquid contact circuit closers turn in unison and in opposite directions. In order that the adjacent circuit closers may also turn in unison, the inner rings 64 are connected by pins 68.

On one of the upper circuit closers is a handle 69 which is provided with a groove 70 which fits over the bead 3. Molded into the handle are two inserts 71 each having forked ends 72 which project from opposite sides of the handle. The ends

72 of the inserts extend between the terminals of the circuit closer and the rings 64, and the ends are bent up into depressions 73 in the rings 64 and thereby hold the handle on the circuit closer. At the four corners of the upper pair of circuit closers 5 are spring strips 74 which bear on the rings 64. The spring strips 74 exert a downward pressure on the circuit closers which increases the contact pressure between the terminals and the contacts 57 and 62. The spring strips are provided with curved ends 75 which fit into depressions 76 in the rings 64 and resiliently hold the circuit closers in either extreme position. The spring strips 74 and the contacts 57 and 62 are secured together by means of hollow rivets 77.

In the assembly of the switch, the handle 69 is placed on one of the upper liquid contact circuit closers and the rings 64 are placed on the terminals over the ends 72 of the inserts 71. The rings 64 are then turned so that the projections 66 fit in the depressions 67 in the terminals, and the ends 72 of the inserts 71 are bent up into recesses 73 in the rings. This locates the handle 69 with reference to the liquid contact circuit closer and secures the handle thereto. The rings 64 are then assembled on the other upper liquid contact circuit closer, and the circuit closers are assembled adjacent each other with the contact strip 62 between the circuit closers. During this assembly, the adjacent rings are connected by 30 the pins 68. The rings 64 are then assembled on the terminals of the lower liquid contact circuit closers, and the circuit closers are assembled adjacent each other with the contact strip 62 between the circuit closers and with the pin 68 connecting the adjacent rings 64. The lower pair of circuit closers is then placed adjacent the upper pair of circuit closers so that the teeth 65 of the rings 64 are in mesh. The contact strips 57 are then assembled against the outer terminals so that the projections 58 and 59 respectively fit in depressions 60 and 61 in the terminals. The springs 74 are then assembled on the contact strips 57 and 62, and the contact strips and springs connected together by hollow rivets 77. The assembly is then inserted within the housing 56 so that the upper ends of inserts 78 molded in the housing project through the hollow rivets 77. The projecting ends of the inserts are then spun over, thereby securing the assembly in the housing. The line conductors are attached to the contacts by terminal screws 79 which are threaded in the inserts 78.

Fig. 11 shows the four-way switch mounted crosswise in a conventional outlet box. The lower end of the housing 56 projects through an opening in the mounting strap 24, and the switch is held on the mounting strap by pins passing through holes 80 in bosses 81 on the housing. The upper end of the housing is enclosed by a cover 82 having two bosses 83 which project through two of the openings 27 in the cover plate 26.

The operation of the switch is shown in Fig. 15. For convenience, the terminals of the switch have 65 been labelled E, F, G, and H, and the switch is shown mounted with the right-hand end of the switch as viewed in Fig. 12 at the top of the outlet box. The handle has been diagrammatically indicated on each of the upper circuit closers. 70 When the handle is in the upper position shown in full lines in Fig. 15, a circuit is completed from terminal E to terminal H and from terminal F to terminal G. When the handle is in the position shown in dotted lines, a circuit is completed 75

from terminal E to terminal G and from terminal F to terminal H.

What I claim as new and desire to secure by Letters Patent in the United States is:

5. 1. In an electric switch, a liquid contact circuit closer operable by rotation about its axis, a support for the circuit closer, a handle on the circuit closer for rotating the circuit closer, and spring means secured to said support for holding the handle on the circuit closer.
10. 2. In an electric switch, a liquid contact circuit closer operable by rotation about its axis and having terminals on opposite sides thereof, a pair of contacts engaging said terminals and supporting said circuit closer for rotation about its axis, a handle on said circuit closer for rotating said circuit closer, a support to which said contacts are secured, and spring means secured to said support for holding the handle on the circuit closer.
15. 3. In an electric switch, a liquid contact circuit closer operable by rotation about its axis having terminals on opposite sides thereof, a pair of contacts respectively engaging said terminals, said contacts and said terminals having complementary ball and socket portions whereby the circuit closer is supported for rotation about its axis, spring means exerting a force on said circuit closer normal to its axis of rotation, and means for securing said spring means and said contacts together.
20. 4. In an electric switch, a liquid contact circuit closer operable by rotation about its axis having terminals on opposite sides thereof, a pair of contacts respectively engaging said terminals, said contacts and said terminals having complementary ball and socket portions whereby the circuit closer is supported for rotation about its axis, spring strips on opposite sides of said circuit closer engaging said circuit closer and exerting a force thereon normal to its axis of rotation, a sheet of insulating material providing a support for the circuit closer, and means securing said strips and said contacts to said sheet.
25. 5. In an electric switch, a liquid contact circuit closer operable by rotation about its axis having terminals on opposite sides thereof, a pair of contacts respectively engaging said terminals, said contacts and said terminals having complementary ball and socket portions whereby the circuit closer is supported for rotation about its axis, spring strips on opposite sides of said circuit closer engaging said circuit closer and exerting a force thereon normal to its axis of rotation, hollow rivets securing said strips and said contacts together, and a housing for said switch having inserts molded therein, said inserts being adapted to extend through said hollow rivets and to be spun over to secure the switch in the housing.
30. 6. In an electric switch for group mounting crosswise in a standard domestic outlet box, a housing open at one end, liquid contact circuit closers in said housing spaced apart one above the other along an axis passing through the open end of the housing with the axes of the circuit closers lengthwise of the outlet box, means for supporting the circuit closers in the housing, a handle projecting through one end of the housing, and means connected to the handle for operating the circuit closers.
35. 7. In an electric switch, liquid contact circuit closers each having an enclosure including cup-shaped terminals on opposite sides thereof, means engaging said terminals for supporting the circuit closers for rotation about the axes of their terminals, members fitting over and secured to a terminal of each of said circuit closers and having intermeshing gear teeth formed thereon, and means for rotating one of said circuit closers.
40. 8. In an electric switch adapted for group mounting crosswise in a standard domestic outlet box, liquid contact circuit closers operable by rotation about their axes, means for supporting said circuit closers one above the other with reference to the bottom of the outlet box with their axes parallel to the length of the box, and manually operated means accessible from the front of the outlet box for rotating said circuit closers.
45. 9. In an electric switch adapted for group mounting crosswise in a standard domestic outlet box, liquid contact circuit closers operable by rotation about their axes, means for supporting said circuit closers one above another with reference to the bottom of the outlet box with their axes parallel to the length of the box, manually operated means accessible from the front of the outlet box for rotating one of said circuit closers, and means connected to said one circuit closer for rotating other of the circuit closers.
50. 10. In an electric switch, a liquid contact circuit closer operable by rotation about its axis and having terminals on opposite sides thereof, members of insulating material on said terminals, a handle for said circuit closer, said handle having metal projections extending between said members and said terminals and bent against the sides of said members for securing the handle to the circuit closer.
55. 11. In an electric switch, liquid contact circuit closers operable by rotation about their axes, each of said circuit closers having an enclosure including cup-shaped terminals on opposite sides thereof, contacts engaging the terminals of each circuit closer, said terminals and said contacts being provided with complementary ball and socket portions whereby said circuit closers are supported for rotation about the axes of their terminals, members of insulating material on said terminals, said members being provided with intermeshing teeth whereby said circuit closers are rotatable in unison.
60. 12. In an electric switch, a support, spaced contacts secured to said support, said contacts having opposed surfaces, a liquid contact circuit closer between said contacts and having an enclosure including cup-shaped terminals on opposite sides thereof frictionally engaging said opposed surfaces, said surfaces and said terminals having complementary ball and socket portions whereby said circuit closer is supported for rotation about the axis of its terminals.
65. 13. In an electric switch, a support, spaced contacts secured to said support, said contacts having opposed surfaces, a liquid contact circuit closer between said contacts and having an enclosure including cup-shaped terminals on opposite sides thereof frictionally engaging said opposed surfaces, said surfaces and said terminals having complementary ball and socket portions whereby said circuit closer is supported for rotation about the axis of its terminals, and spring means secured to said support for exerting a force on the circuit closer normal to its axis of rotation for increasing the contact pressure between the terminals and the contacts.
70. 14. In an electric switch, a liquid contact circuit closer having an enclosure including opposed

75. 75

cup-shaped terminals, contacts engaging said terminals, said contacts and said terminals having complementary projections and depressions formed therein whereby said circuit closer is supported for rotation about the axis of its terminals, a handle on said circuit closer for rotating said circuit closer, a support to which said contacts are secured, and spring means secured to said support for holding the handle on the circuit closer.

10. 15. In an electric switch, a liquid contact circuit closer having an enclosure including opposed cup-shaped terminals, contacts engaging said terminals, said contacts and said terminals having complementary projections and depressions formed therein whereby said circuit closer is supported for rotation about the axis of its terminals, a handle fitting over said terminals, said handle and said terminals having interfitting portions for preventing relative rotation therebetween, arcuate flanges extending from each side of said handle, a support to which said contacts are secured, and spring means secured to said support and engaging said flanges for holding the handle on said terminals.

15. 16. In an electric switch, a liquid contact circuit closer having terminals on opposite sides thereof, a pair of contacts respectively engaging said terminals, said contacts and said terminals having complementary projections and depressions therein whereby the circuit closer is supported for rotation about the axis of its terminals, and a housing for said switch having inserts molded therein, said inserts being adapted to extend through openings in said contacts and to be spun over to secure the switch in the housing.

17. In an electric switch, a housing, liquid contact circuit closers arranged one above the other in said housing, said circuit closers having terminals facing the side walls of the housing, contact strips between said terminals and said side walls and extending longitudinally thereof toward the ends of the housing, said contact strips being spaced one above the other, and said contacts and said terminals having inter-engaging projections and depressions providing bearing surfaces whereby the circuit closers are supported for rotation about the axes of their terminals, flanges on said contacts at the ends of the housing facing the top of the housing and extending inwardly from the walls thereof, said flanges being provided with means for attaching conductors thereto, supports beneath said flanges, and means securing said flanges to said supports.

18. In an electric switch, a housing, liquid contact circuit closers having opposed terminals facing the side walls of the housing, contact strips extending along said walls between the terminals and said walls, said strips and said terminals having inter-engaging bearing surfaces whereby the circuit closers are supported for rotation, the diameter of said bearing surfaces being relatively great compared to the thickness of the strips, and rings of insulating material non-rotatably carried on said terminals, said rings having intermeshing gear teeth whereby the circuit closers are turned in unison and said rings being located between said contact strips and held on the terminals by said strips.

ROBERT F. SAMBLESON. 35
